DESIGN FOR A CIGAR LIGHTER HANDLE

Bert G. Cochrane, Chicago, Ill., assignor to Casco Products Corporation, Bridgeport, Conn., a corporation of Connecticut

Application December 9, 1936, Serial No. 66,400

Term of patent 14 years

To all whom it may concern:

Be it known that I, Bert G. Cochrane, a citizen of the United States, residing at Chicago, in the county of Cook and State of Illinois, have invented a new, original, and ornamental Design for a Cigar Lighter Handle, of which the following is a specification, reference being had to the accompanying drawing forming part thereof.

Fig. 2 is a side elevation of the handle.
Fig. 3 is a front view of the handle.

Fig. 4 is an edge view of the handle.

I claim:

The ornamental design for a cigar lighter handle, as shown.

BERT G. COCHRANE.
